UNITED STATES PATENT OFFICE.

ALBERT E. STEWART, OF FRANKLIN, NEW HAMPSHIRE, ASSIGNOR TO ACME KNITTING MACHINE & NEEDLE COMPANY, A CORPORATION OF NEW HAMPSHIRE.

KNITTING-MACHINE.

1,152,373.

Specification of Letters Patent. Patented Aug. 31, 1915.

Application filed May 5, 1913. Serial No. 765,429.

To all whom it may concern:

Be it known that I, ALBERT E. STEWART, of Franklin, in the county of Merrimack and State of New Hampshire, have invented 5 certain new and useful Improvements in Knitting-Machines, of which the following is a specification, reference being had to the accompanying drawings, forming part thereof.

10 This invention has reference to improvements in knitting machines and relates particularly to improvements therein whereby yarns or threads may be cut at or about the time the knitting operation reaches a point 15 at which, heretofore, such yarn ordinarily has been floated.

One object of the invention is to so construct a knitting machine having any ordinary and well known yarn changing devices 20 that at or about the operation of changing the yarn, particularly during the knitting of the foot and sole of stocking either of the yarns may be engaged and cut so that no floating of the yarn is necessary, the yarn 25 heretofore used in floating is saved, and the subsequent operation, heretofore employed of cutting out the floated yarn is avoided.

Another object of the invention is to improve the construction of yarn or thread 30 cutters for knitting machines.

Another object of the invention is to provide improved yarn or thread cutters respectively for any two yarns which it is desired respectively to cut at certain points in 35 the operation of the machine and to operate said yarn or thread cutters independently.

Other objects of the invention will appear from the following description.

The invention consists in such novel features of construction and combination of parts as shall hereinafter be more fully described and pointed out in the claims.

Figure 1, represents a vertical sectional view of the latch ring portions of a knitting 45 machine illustrating this invention. Fig. 2, represents a plan view of the same. Fig. 3, represents a sectional view of parts taken on line 3—3 Fig. 3, looking in the direction indicated by the arrows of said line. Fig. 4, represents a diagrammatic view to illustrate the relative positions of some of the parts. Fig. 5, represents a detail plan view of parts of one of the yarn engaging and cutting devices.

Similar characters of reference designate 65 corresponding parts throughout.

As shown in the drawings in its preferred form, 5 represents the latch ring which is supported by the post 6 mounted on the cam ring, of which a fragment 7 is shown. 60 Post 6 has the shaft 8 on which are mounted to swing the yarn change arms of which but two, 9 and 10, are shown in the drawings, to avoid confusion. Arm 9 has the usual guide 12 for the yarn adapted to form the 65 high splice and reinforced sole and arm 10 has the guide 11 carrying one of several yarns used in making the stocking. These arms 9 and 10 are operated by any usual mechanism in any well known manner to, at 70 times, carry the respective yarns passing through their guides to positions at which said yarns may be engaged by the needles N, N of the usual needle cylinder, and at other times to move or withdraw said yarns 75 from such positions.

Mounted in the post 6 of the latch ring is the shaft 14 on which are pivotally mounted the bell crank levers 15 and 16 adapted to be actuated at times by means of the members 80 17 and 18, the bell crank lever 16 having the retracting spring 19 one end of which is secured in the collar 20 fixed to said shaft 14. Said members 17 and 18 are intermittently actuated at or about the time at which their 85 related yarn carriers 9 and 10 are operated to withdraw their respective yarn guides 11 and 12 from the points at which said guides deliver yarn to the needles, by the usual cams C and C, C on the drive shaft S which 90 is the drive shaft for the needle cylinder.

Located within the latch ring and supported by the goose neck 23 is the plate 24, with reference to which plate 24, the needle cylinder, in some machines, is relatively 95 movable. This plate 24 has the upwardly curving thread engaging arm 25 adapted to engage the main thread B and guide said thread into the slot 26 of said plate during the upward movement of the yarn guide 12. 100 Mounted on said plate 24 is a post on which is journaled the sleeve 27 having at its upper end the crank arm 28 actuated from bell crank lever 16 by the connecting rod 29 while at its lower portion said sleeve 27 has 105 the arm 30 having at its outer end the spring opened pivoted yarn carrying and cutting blades 31 and 32 of which the latter has the

cam extension 33, 34 which coöperate with the way 35 when the free end of arm 30 is swung toward the center of plate 24, to close blade 32 over blade 31 to, ultimately, cut a 5 yarn or thread engaged therebetween. Normally these blades 31 and 32 are located as shown in Fig. 2 in full lines, so that the main thread B guided along slot 26 will enter between said blades.

10 Mounted on the plate 24 above cam 36 is the yarn guide plate 37 which extends to the edge of slot 26 and has the superposed spring yarn clip 38. Pivotaly mounted in the arm 39 extending upward from cam 36 15 is the yarn holder arm 40 which is adapted when depressed by its spring 41 to hold a positioned yarn against the block 42, on plate 24, as shown, to hold said yarn B under a tension between the point at which 20 the yarn B is cut and the yarn guide 12. This yarn holder 40 has the crank arm 43 which is engaged by the collar 44 on slide rod 45 connected with and actuated by the swinging arm 30 so that when the blades 31 25 and 32 are in the open position the holder arm 40 is always raised.

On the slide 46 is the pin 47 which is connected by a spring with the guide 48. Said slide at its forward end, is furnished with 30 the hook 49 for engaging the splice thread or yarn A and has the exterior upwardly extending members 46' furnished with the stops 50 and 51. Slide 48 is operated by a bell crank lever 52 pivotally mounted on 35 part 53 of plate 24 and actuated to draw the splice yarn A by means of hook 49 to a position to be cut by means of the rod 54 connected with said bell crank lever and with the bell crank lever 15.

40 Fixed at the forward end of guide 48 is the cutter jaw 55 and pivotally mounted on said guide is the coöperating jaw 56 having the arm 57 which extends between and is actuated by the stops or lips 50, 51 on said 45 slide 46 to effect the closing of said jaw 56 after the hook 49 has been partially retracted, the additional movement of said slide 46 and its hook being permitted by the space between stops 50 and 51 being greater than 50 the diameter of the arm 57 of jaw 56.

During the rotation of shaft S cams C and C, C, act alternately on their related rods 17 and 18 and actuate the yarn changers or yarn carrying arms to move the guide 55 ends of said arms into and out of the yarn delivery positions. In coördination with the changing of the yarns the yarn engaging

devices are operated to engage the respective yarns and carry them to positions at which said yarns are cut and their ends are 60 held from drawing back through the yarn guides. Thus the yarns which are out of the position to be taken by the needles instead of being floated, are cut and the length of yarn ordinarily floated is saved. The 65 subsequent operation of cutting out all the floated yarns, after the knitting operation being also avoided.

While I have herein shown one embodiment of my invention it is not my intention 70 thereby to limit my invention to the particular mechanism herein shown and described.

Having thus described my invention I claim as new and desire to secure by Let- 75 ters Patent.

1. A knitting machine comprising in combination, a latch ring, a plate sustained within said latch ring and having a yarn engaging slot open at the periphery of said plate, a spring yarn engaging device having a member extending transversely of said slot, a yarn carrier pivotally mounted on said plate to engage a yarn in said slot, a yarn engaging device having a reciprocating yarn engaging hook, a pair of yarn severing devices adapted to coöperate respectively with said yarn carrier and with said hook, a pair of yarn guides movably mounted to deliver yarn, means for operating said yarn guides in succession, and mechanism operated by said yarn guide operating means for actuating said yarn carrier and said hook and their respective yarn severing devices relative to the operation of 95 their related yarn guides.

2. A knitting machine comprising a pivoted arm having a yarn guide adapted to deliver to the needles, a plate mounted relative to the needles and having a thread receiving slot, a spring yarn engaging device having a member overlapping said slot, a carrier arm pivotally mounted on said plate, means for swinging said carrier arm across said slot, a pair of yarn engaging plates pivotally mounted on said carrier arm, and means mounted on said plate and coöperating with one of said yarn engaging plates to effect the swinging thereof.

ALBERT E. STEWART.
